REGISTER

Frederick W. Kulicke, Philadelphia, Pa., assignor
to Mitchell Specialty Company, Philadelphia,
Pa., a corporation of Pennsylvania

Application March 24, 1931, Serial No. 524,865

4 Claims. (Cl. 98—101)

My invention relates to devices, commonly known as registers, for regulating and controlling the discharge of air through and from a flue terminating in a room to be heated or ventilated. The present invention relates primarily to registers for use in automobiles to control the discharge thereinto from a pipe or flue of air which has been heated by its passage in contiguous relation to the motor or some part heated by 5 the exhaust gases from such motor.

The general object of the invention is to provide a register of simple construction and of a character such that it may be manufactured at a minimum of expense or cost.

15. It also is an object of the invention to provide a register embodying novel means of a character such that the means for controlling the discharge of air, warm or cold, from the flue may be adjusted readily to any position desired.

20. To the foregoing and other ends the invention comprehends the construction as hereinafter described in detail, particularly defined in the claims, and as shown in the drawing wherein I have illustrated a construction embodying the 25 invention in the form which at present is preferred by me. It will be understood that changes in the details of construction may be made within the scope of the claims appended hereto without departing from the invention.

30. In the drawing:

Fig. 1 is a view showing in cross section the device embodying my invention, also showing in longitudinal section a portion of the front end of a pipe or flue upon which the said device is 35 mounted, and also showing in section a fragmentary portion of a wall of an inclosure such, for example, as an automobile body;

Fig. 2 is a view in front elevation, looking toward the left in Fig. 1; and

40. Fig. 3 is a view in inside or rear elevation of the device shown in Figs. 1 and 2.

In the use of the register for controlling the discharge of warmed or heated air into the interior of the body of an automobile it usually is 45 mounted at the front of the automobile upon the dash board or any other part or portion of the front wall of the structure. However, it is to be understood that the register may be mounted upon the bottom of the automobile. Although 50 the register is intended primarily for use for controlling the admission of heated air to the interior of an automobile body it is to be understood that it also may be used for controlling the admission of air into the rooms of dwellings or other like structures.

In the drawing I have shown at 1 the outer or discharge end portion of a pipe or flue from which air, usually heated, is discharged. The end portion thereof projects through an opening 2 provided in a wall 3, such as the front end portion of the body of an automobile. The end of the pipe or flue 1 projects a short distance beyond the inner side of the wall 3 as shown in Fig. 1. The device embodying my invention is mounted on the outer or discharge end of the said pipe or flue. The device comprises a base or supporting member consisting of a plate 5 having an opening 6 centrally located therein. The edge of the said opening is provided with an inwardly or rearwardly extending flange 7 slotted at intervals as indicated at 8 so as to provide relatively narrow portions which are more or less yielding and which are resilient. The slotted flange 7 is adapted to be inserted in the open end of the pipe or flue 1 and the frictional engagement thereof with the inner side of the said pipe holds the said base member in position on the said pipe. It will be apparent that the plate 5 may be rotated about the axis of the pipe 1 so as to adjust the same to any position desired. The outer edge of the plate 5 is provided with a relatively wide projection 10 the opposite edges of which have rearwardly projecting ears 11. These ears are arranged in parallel relation to each other and each of them is provided on its rear edge with a series of notches 12 for a purpose which hereinafter will be explained. The upper edges of the said ears preferably are concave as indicated at 13.

For the purpose of regulating and controlling the discharge of air or any other gas from the pipe or flue 1 I have provided a cover and deflector 15 consisting of a metal plate. An annular portion 16 of the plate 15 is flat and adapted to be seated in contact with the outer surface of the plate 5 outside of and surrounding the opening 6. The outer edge of the annular flat portion 16 of the plate 15 is bent and extended rearwardly as shown at 17. Such rearwardly bent portion is of a character to add to the ornamental appearance of the register but it also tends to cause greater dispersion of the air which escapes from the pipe or flue 1 and impinges upon the inner or rear surface of the cover and deflector plate 15. The plate 15 is provided with a relatively wide projecting portion 20, the side and end portions of which are provided with flanges 21 and 22 respectively. The side flanges overlie and for the most part conceal the ears 11 at the opposite side edges of the projection 10 of the plate 5.

For the purpose of pivotally connecting the 110

cover and deflector plate 15 to the ears 11 I have provided pivots 23 which extend through the ears or projections 11 and the side flanges 21. These pivots serve to connect the cover and deflector plate 15 to the ears or projections 11 upon the base member of the register but at the same time permit pivotal movement of the said cover and deflector as indicated by the dash and dot lines at 25 in Fig. 1 of the drawing.

For the purpose of retaining the cover and deflector both in closed position and in any open position to which it may be adjusted I have provided a spring plate catch 26 upon the inner side of the flange 22. The intermediate central portion of the plate 26 is secured to the corresponding portion of the flange 22 by means of rivets 27. The opposite end portions of the said spring plate 26 are bent inwardly away from the flange 22, as shown in Fig. 3 of the drawing, and terminate in slightly inwardly extending reduced portions 28 the inner surfaces of which are rounded as indicated at 29 in Fig. 1 for engagement with the notches 12 in the ears of projections 11 and also with the rear end portions of the concaved edges 13 of the ears 11. When the cover and deflector is in closed position as shown in full lines in Fig. 1 the portions 28 engage the outer edges of the ears or projections 11 in adjoining relation to the notches therein, as shown in Fig. 1.

If it is desired to adjust the cover and deflector to an open position it is but necessary to take hold of the edge portion thereof and exert an outward pull thereon, whereupon the outer end portions of the spring 26 will yield to permit the movement thereof over the teeth between the notches 12 to thereby permit the movement of the cover and deflector to any open position which may be desired. The rounding of the reduced portions 28 as indicated at 29 and the tapering and rounded projections between the notches upon the ears or projections 11 facilitate the movement of the cover and deflector from either closed to open or from open to closed position.

By rotatably adjusting the device with respect to the discharge end of the pipe or flue 1 the direction of the flow of air as it is discharged from the pipe or flue and from the register may be controlled. The frictional action of the portions of the flange 7 intermediate the notches 8 therein operates to hold the device in any position to which it may be adjusted upon the outer discharge end of the pipe or flue 1.

It will be seen by my invention I have provided a register of extremely simple construction and of a character such that it may be manufactured at a minimum of cost and expense, and also that the device embodying the invention is of a character such that it is highly suitable for use in the regulating and controlling of the discharge of heated air into the interior of the body of an automobile.

Although the device has been designed primarily for use in connection with automobile bodies it is apparent that it may be used for controlling the discharge of air into the rooms of structures of other character.

Having thus described my invention, what I claim and desire to secure by Letters Patent is:

1. A register, comprising a base plate having a projection extending outwardly from one edge thereof the opposite edges of which are provided with rearwardly extending ears, the said plate having an opening therethrough, a cover and deflector for controlling the passage of air through said opening, the said cover having a projection from one edge thereof which projection is provided with side flanges and an end flange, means for pivotally connecting the said side flanges to the said ears, and means in engagement with the said ears for retaining the said cover and deflector in any position to which it may be adjusted. 80

2. A register for controlling the discharge of air from a flue, comprising a base plate having an opening therethrough from the edge of which a rearwardly extending flange projects, a projection extending from one edge of the said base plate, the opposite edges of the outer end portion of said projection having rearwardly extending ears the rear edges of which are provided with notches, a cover for controlling the passage of air through said opening, means for pivotally connecting the said cover to the said base plate, and means on said cover cooperating with said notches for holding the said cover either in closed position or in any open position to which it may be adjusted. 85

3. A register for controlling the discharge of air from a flue, comprising a base plate having an opening therethrough and having a flange extending rearwardly from said opening, which flange is provided with slots at intervals therein to form slightly yielding resilient portions for engaging the end of the said flue for adjustably supporting the base plate thereon, the said base plate having ears projecting rearwardly from an edge portion thereof the rear edges of which are provided with notches, a cover and deflector plate for controlling the discharge of air from the said flue, means for pivotally connecting said cover plate to the said ears, and a spring device supported by the said cover plate and engaging the notches in the said ears for holding the said cover and deflector plate in any position to which it may be adjusted about the axis of its pivotal movement. 100

4. A register for controlling the discharge of air from a flue, comprising a base plate having an opening therethrough, means for securing said base plate to the open end of said flue, the said base plate having a projection extending outwardly from one edge thereof, said projection having rearwardly extending ears provided with notches upon their rear and inner edges, a cover and deflector plate for controlling the discharge of air from the said flue, said cover and deflector plate having a projection at one edge thereof of the opposite sides and outer edges of which are provided with rearwardly extending side and end flanges, pivots for pivotally connecting the said side flanges with the said ears, and spring means mounted upon the end flange for engaging the said notches for holding the said cover and deflector plate in any position to which it may be adjusted. 110

FREDERICK W. KULICKE.

CERTIFICATE OF CORRECTION.

Patent No. 1,968,560.

July 31, 1934.

FREDERICK W. KULICKE.

It is hereby certified that error appears in the printed specification of the above numbered patent requiring correction as follows: Page 2, line 23, for "of" read or; line 53, after "seen" insert that; and line 140, claim 4, before "position" insert open; and that the said Letters Patent should be read with these corrections therein that the same may conform to the record of the case in the Patent Office.

Signed and sealed this 11th day of September, A. D. 1934.

Leslie Frazer
